HEATER

Filed June 25, 1923

FIG. 3.

Inventor:
Wm. A. McGlamery

UNITED STATES PATENT OFFICE.

WILLIAM A. MCGLAMERY, OF ASHEVILLE, NORTH CAROLINA.

HEATER.

Application filed June 25, 1923. Serial No. 647,763.

To all whom it may concern:

Be it known that I, WILLIAM A. MCGLAMERY, a citizen of the United States, residing at Asheville, in the county of Buncombe and State of North Carolina, have invented new and useful Improvements in Heaters, of which the following is a specification.

This invention relates to heaters.

10 The primary object of the invention is to provide a heating device in the nature of an open grate type whereby the products of combustion from the grate basket are deflected against the front wall of the heater, 15 and are retarded in their passage to the smoke pipe.

A further object is to provide a heater constructed in a manner whereby the heat conveying pipe may be associated therewith 20 to heat a drum in a room arranged above the room containing the heater.

A still further object is to provide a heater of novel construction whereby the heat will be more readily conserved thereby 25 preventing waste of fuel.

This invention also consists in certain other features of construction and in the combination and arrangement of the several parts, to be hereinafter fully described, 30 illustrated in the accompanying drawings and specifically pointed out in the appended claims.

In describing my invention in detail, reference will be had to the accompanying 35 drawings wherein like characters denote like or corresponding parts throughout the several views, and in which:—

In the drawings:

Figure 1 is a side elevation of the heater 40 forming the subject matter of this invention.

Figure 2 is a vertical section of the device in Figure 1.

Figure 3 is a front elevation thereof.

45 Figure 4 is a rear view.

Figure 5 is a view illustrating the installation of the heater and manner of applying a heat conveying pipe thereto and to a drum respectively when it is desired to heat 50 a room disposed above the room containing the heater.

Referring to the drawings in detail, A indicates a fragmentary portion of a room with one wall thereof broken away showing 55 the installation of my improved heater. The heater is novel shaped and the lower

portion 1 thereof is arranged out of line with the upper portion 2 which is connected to the lower portion through the medium of the upwardly inclined intermediate portion 3 as shown. Transversing the rear side of the heater at a point adjacent the juncture of the lower portion and the intermediate portion, there is a bar 4 adapted to support the masonry of the wall of the room, as 60 clearly shown in Figure 5 of the drawings. This view also discloses the means of applying the heat conveying pipe 5 to the heater and this pipe rises from the top 6 and terminates within the heating drum B arranged in the room C above the room A. While one pipe is shown, it will be apparent that any reasonable number can be employed. 65

Detachably secured to the front of the upper portion 2 of the heater, through the medium of the headed bolts 7, there is a plate 8 which will be termed the front plate. It should be noted that the upper portion 2 is of less size and narrower than the remaining portions of the heater and secured to the inner side of the plate 8 there is a plurality of superposed elongated deflector plates 9 which are adapted to deflect the heat against the front plate and which have 80 a tendency to prevent escape of heat through the chimney. The front plate collects a maximum amount of the heat which in turn throws it out into the room A. However, a sufficient amount will be allowed to pass 85 through the slots 9' of the plates to be conveyed to the heating drum, as above set forth. The slots 9' also allow the smoke to gain access to the smoke pipe 11 which extends from the rear wall of the upper portion and pivotally secured to the inner side of the rear wall is a valve 11' controlling the adjacent end of the pipe 11 and acting as a damper therefor. 90

The front of the lower intermediate portion of the heater is open as shown and disposed within the lower portion in a manner to engage the rear wall thereof is a grate basket 12 which is arranged below the curved rear wall 13 of the intermediate portion 3. By this wall 13 being thus constructed, it will be readily seen that the heat, etc., will be deflected upwardly to the plate 8 which in turn together with the deflector plates will deflect the heat, as above set forth. 100

Formed in the rear wall 13 adjacent its

juncture with the rear wall of the bottom portion there is an opening 14 controlled by a hinged draft door 15. The door is operated by an angular bent handle member 16 extending forwardly and terminating in an eyed hand hold 16'. The rear end of the handle member is pivotally secured to one end of the door carrying member 17 which underlies the bar 4 and is received in the apertured ears 18 formed at the ends thereof as shown.

An ash pan 19 extends from the rear wall of the lower portion below the grate basket and removably secured to the side walls of 15 the rear portion there is a hearth guard 20 which extends across the entire front in a manner to prevent hot ashes, etc., from coming in contact with portions of the floor of the room, as well as to provide a convenient 20 foot rest, as will be readily apparent.

The heater can be constructed from any desired metal and by its peculiar shape can be readily installed in an advantageous position in any room to be out of the way and 25 yet provide sufficient heat and also a great saving in fuel consumption.

The heat conveying pipe 5 is detachably secured to the top of the heater and when it is desired not to utilize the heat when conveying heat to the adjacent rooms, a suitable 30 cap 21 is adapted to cover the collar 22 which receives the lower end of the heat conveyor pipe.

It is thought from the foregoing description that the advantage and novel features 35 of my invention will be readily apparent.

I desire it to be understood that I may make changes in the construction and in the combination and arrangement of the several parts, provided that such changes fall 40 within the scope of the appended claims.

Having thus described my invention, what I claim as new is:—

1. A heater of the character described 45 comprising a lower portion, an upper por-

tion, and an upwardly inclined intermediate portion connecting the portions first mentioned, said intermediate and lower portion being provided with an open front, a grate basket fixed to the rear wall of the lower portion in a manner to underlie the rear inclined wall of the intermediate portion, a draft door controlling an opening arranged 50 in the rear wall of the intermediate portion above the grate basket, means extending to the front of the heater for operating said draft door, a plate detachably secured to the side edges of the upper portion and slotted deflector plates curved downwardly and extending from the inner side of said plate as 55 and for the purpose specified.

2. A heater of the character described comprising a lower portion having an open front, an upper portion arranged out of line with the lower portion, an intermediate portion having an open front and connecting the upper and lower portions, a transverse bar extending across the back of the intermediate portion adjacent the juncture thereof with the lower portion and being adapted 60 to support masonry in the installation of the heater.

3. A room heater of the character described comprising a lower portion, an upper portion, and an upwardly inclined intermediate portion connecting the first mentioned portions, a detachable front for the upper portion, a top for the upper portion, a heat pipe detachably secured to said top, an upper room, a heating drum therein 65 to receive the heat pipe, a smoke pipe extending from the rear wall of the upper portion, a basket grate portion fixed within the lower portion at the juncture thereof with the intermediate portion an ash pan arranged below the basket grate and a hearth guard detachably secured to the side edges of the lower portion for the purpose specified.

WM. A. McGlamery.
